[57] CLAIM

The ornamental design for a door closer unit, as shown and
described.

DESCRIPTION

FIG. 1 is a top, front, and left side perspective view of a door
closer unit showing our new design;

FIG. 2 is a left side elevational view thereof, the right side
being a mirror image of that shown;

FIG. 3 is a front and left side perspective view thereof;

FIG. 4 is a horizontal cross-sectional view thereof, taken
along line 4—4 of FIG. 2;

FIG. 5 is a top plan view thereof; and,

FIG. 6 is a front elevational view thereof.
